CLAIM

The ornamental design for a combined game board with set of game pieces as shown and described.

DESCRIPTION

1. Combined game board with set of game pieces

1.1: Front, top, right perspective view of the combined game board with set of game pieces showing our new design in a position of use;

1.2: Front, top, right perspective view of the game board thereof shown separately for clarity of illustration;

1.4: Front, top, right perspective view of the set of game pieces thereof shown separately for clarity of illustration;

1.5: Back, bottom, left perspective view of the set of game pieces thereof shown separately for clarity of illustration;

1.6: Back, top, left perspective view of the set of game pieces thereof shown separately for clarity of illustration;

1.7: Front, bottom, right perspective view of the set of game pieces thereof shown separately for clarity of illustration; and

1.8: Bottom plan view of the combined game board with set of game pieces.

The broken lines in the reproductions depict environmental structure of the combined game board with set of game pieces that forms no part of the claim.

1 Claim, 8 Drawing Sheets
